UNITED STATES PATENT OFFICE

2,503,807

ARTIST'S EQUIPMENT

Michael Dolas, New York, N. Y.

Application September 17, 1946, Serial No. 697,418

5 Claims. (Cl. 45—69)

1

This invention relates to equipment for use by artists, illustrators, draftsmen, etc., and more particularly to a compact, unitary unit comprising all of the needs of persons engaged in these professions, which can be compactly placed into a trunk which can be conveniently transported and set up for use on short notice.

Artists, draftsmen, illustrators, etc., who will be referred to herein under the generic designation as artists, depending upon the precise work they are doing, require a large variety of equipment, such as easels, drawing boards, pallets, etc., most of which are bulky and inconvenient to transport and set up for use in various places. Most of such equipment is designed to remain stationary in a permanent studio.

In accordance with my invention, I have developed a compact, unitary structure containing all the necessary equipment for an artist which can be housed together, such as in a trunk, which may be shipped and transported from place to place with the ease of luggage. If an artist wishes to work in a hotel room or other temporary working accommodations, for example, it is necessary only for him to take the trunk with him just as he would travelling baggage, and all of his needs are available upon opening the trunk and placing the various component parts in the desired positions for use. The equipment is not rendered less suitable for use because of this convenience.

My invention is adapted to be embodied in housings other than trunks, such as a cabinet which can be constructed as a permanent piece of furniture for a studio or room. However, merely for illustrative purposes, I will describe my invention herein as applied to a trunk which can be readily shipped. The embodiment used for illustrative purposes can be better understood from the detailed description hereinafter, taken in conjunction with the accompanying drawings, in which:

Figure 1 is a perspective view showing the equipment in position for use as an easel;

Figure 2 is a front elevation showing the easel lowered;

Figure 3 is a detail view partly in elevation and partly in perspective showing the manner in which the pallet is secured;

Figure 4 is a front elevation on a reduced scale illustrating the use of the equipment as a drawing board;

Figure 5 is a view in perspective showing the drawing board removed to expose the mounting means therefor;

Figure 6 is a side elevation showing the easel in

vertical position extended to accommodate a large canvas;

Figure 7 is a side view in cross section showing a detail of the easel mounting construction;

Figure 8 is a perspective looking from behind showing a rear view of the easel mounting means;

Figure 9 is a cross sectional view of the support for the easel;

Figure 10 is a view mostly in cross section illustrating a detail of the construction for holding the easel support in position;

Figure 11 is a view in cross section illustrating the manner in which the easel is mounted on the easel support;

Figures 12 and 13 are plan and cross sectional views, respectively, of the construction employed for securing the easel to the easel support.

Referring to the figures more particularly, the portable equipment comprises a trunk indicated generally at 10. The trunk may have the usual handles 11 (Fig. 5) by which the trunk may be moved. The lid 12 of the trunk is shown in open position in all of the figures but may be held in closed position by latches 13 and a lock 14. The trunk preferably is formed so that the lid normally forms one of the vertical sides, when closed, as distinguished from the top which is the common position of the lid of most trunks when closed. The lid is hinged to the trunk by suitable hinges 15, which are strong enough and of such construction as to permit the lid to fold back and lay flat upon the upper surface 16 of the trunk.

The interior of the trunk in the embodiment illustrated is provided with three compartments comprising two drawers 17 and 18 (Fig. 1), which can be pulled out and into which brushes and miscellaneous artists' supplies can be kept. An upper section above the drawers is closed by a cover 19 which can be dropped to expose a plurality of compartments 20 (Fig. 2) into which drawing paper and other supplies can be stored. The cover 19 preferably is made out of plywood, or other soft wood, and can function as a bulletin board on which reminders, sketches, etc., can be fastened with thumb tacks, either on the outside face when in closed position or on the interior face when the cover is dropped open to expose the compartments 20, as shown in Fig. 2.

Preferably, the interior surface is so used because this surface is normally in front of the artist when the cover 19 is dropped on hinges 23, and any material fastened to the interior surface is always in view as a constant remainder, such as work to be done, appointments, etc.

Above the compartments 20 is a drawer 21

which is mounted on racks 22 (Figs. 1 and 5) so that the drawer can be pulled out to extend beyond the side of the trunk. The drawer thus forms a convenient place to keep brushes, erasers, and miscellaneous equipment immediately below the easel or drawing board for ready access to the artist who is working in front of it, as shown in Fig. 1.

The drawers 17 and 18, the compartments 20 behind the cover 19, and the drawer 21 do not extend the full depth of the trunk so as to leave spaces noted as *a* and *b* (Fig. 5), which are deep enough to accommodate the drawing board and all of the equipment fastened on the inside of the lid, as will be described more particularly hereinafter. Preferably, the depth of the space *a* is sufficient so that the drawing board and easel on the inside of the cover do not occupy the entire space and leave sufficient room in space *b* for a large canvas or other drawing material to be stored or carried, provided they are not larger than the inside dimensions of the trunk.

The exact arrangement of the drawers 17 and 18, the compartment 20 and the drawer 21 is subject to variation, provided that it is suitably subdivided to hold the various equipment required by the artist. The depth of these drawers and space similarly can be varied, depending upon the amount of space *b* desired in which to store large sheets of drawing material. It is highly desirable to include the drawer 21 and to mount this for sliding movement on guides 22 so as to permit the drawer to be pulled out beyond the upper surface 16 of the trunk so as to be readily accessible to the artist during work.

I will next describe the easel or drawing board which is mounted on the upper surface of the lid 12 when open, which would be the interior surface of the lid when closed into the space *a*.

On the inside surface of the lid 12, which is the upper surface when open, are mounted two paint boxes 24 and 25. On top of each box is a cover 26 which is removable and which can be used as a pallet. The pallets may be formed of metal, such as aluminum, and suitably shaped with rims 26a. Within the boxes 24 and 25 may be stored tubes of paint and other artists' material. When the equipment is in use, these covers may be removed, exposing the interior 24a of the box (Fig. 1). Either of the pallets 26 may be fastened to the pallet holder, as shown more particularly in Fig. 3, and which will be described in greater detail hereinafter. The pallets 26 are held in place as covers for the paint boxes 24 and 25 by the easel or drawing board which immediately overlies them when the drawing board or easel is in flat position. Between the paint boxes is a space generally indicated at 27 (Fig. 8) into which the drawing board or easel support 34 fits when in retracted position. From this construction it will be seen that when the easel or drawing board is fastened on the support 34 and the support 34 lowered to fit into the space 27 between the paint boxes, the drawing board will act to hold the cover pallets 26 on top of the paint boxes 24 and 25, as shown in Fig. 2.

The easel and drawing board support 34 will now be described in greater detail. Mounted on one edge of the lid 12, nearest the hinges, is a supporting member 29 on which a long piano hinge 30 is fastened, (Fig. 7). One side 31 of the piano hinge is fastened to the supporting member 29 by screws 31a, and the other side of the piano hinge is fastened to a large triangular plate 33. Suitable bolts 35 may be used for fastening the

piano hinge to the triangular plate 33. The use of the piano hinge 30 for this purpose is important since it is a long and continuous support which is essential for the adequate and steady support of the easel or drawing board.

Fastened to the triangular piece 33 is a rectangular support, generally indicated at 34, on which the drawing board or easel is mounted. Preferably, this is formed so as to leave a hollow interior space 35. The support 34 is fastened to the triangular plate 33 by means of suitable screws or bolts 36. The support 34 is illustrated in cross section more particularly in Fig. 9, showing the hollow space 35, the sides 37 and the extensions 38. This cross section extends the full length of the support 34. This construction for holding the support is important to give the necessary rigidity to the easel or drawing board. The solid triangular shape of the plate 33 similarly contributes to the solidity necessary for construction of this type.

About midway on the support 34 is a holding means, generally indicated at 39 in Figs. 6 and 8 and shown in greater detail in Fig. 10, for positioning the support 34. Two side members 40 and 42 are fastened to the sides 37 of the support 34 by means of bolts 41 or other securing means. For reinforcement purposes a U-shaped piece 43 is bolted to the support 34 by means of bolts 41a. Two holes 44 are formed in the overlapping sides 40 and 42 through which extend the cross-arms 46 of a T-member 45. The arms 46 and 47 which extend through the holes 44 are secured with nuts 48 on each end. The other portion of the T-member 49 telescopes into a tube 50 (Fig. 8). One end of this tube 50 is adapted to be secured by means of a thumb bolt 51 (Fig. 8) to the upper surface of the lid 12 in the space 27 between the paint boxes 24 and 25. Any construction for fastening the lower end of the tube 50 to the upper surface of the lid 12 may be utilized and a plurality of brackets 50a, 50b, 50c, etc., spaced from each other may be positioned so that the end of the tube 50 may be fastened at different points by the screw 51. The other end of the tube 50 is provided with a thumb screw 52 which is adapted to firmly secure the end 49 of the T-member. The brackets 50a, 50b and 50c spaced along the surface of the lid can be used in coaction with the bolt 51 to fasten the lower end of the tube 50 at various points along the space 27. By means of the construction shown, the support 34 may be held in any desirable inclined position by fastening the lower end of the tube 50 by means of the bolt 51 to one of the different brackets 50a, 50b, 50c on the surface of the lid or by sliding the end 49 of the T-member in and out of the tube 50 and securing it at the desired position. If desired, the support 34 may be placed perfectly vertical, as shown in Fig. 6, or it may be placed at any angle, as shown in Figs. 1 and 8.

When the lid 12 is to be closed, the thumb screw 51 is removed so that the lower end of the tube 50 can be disengaged from the bracket and in this way the support 34 may be laid out flat between the two paint boxes, as shown more particularly in Fig. 5.

Attached to the upper end of the support 34 is a movable fastener 53 (Fig. 8) having two grooves 54, which can coact with the screws 55 extending from the upper surface of the lid 12 so as to lock the support 34 in retracted position between the paint boxes, as shown in Fig. 5. This locking member 53 may be suitably hinged, as shown at

56, so that the grooves 54 may be slid under the heads of the screws 55.

The drawing board or easel, which is mounted on the support 34, is formed from a solid piece 60, preferably of wood. The board 60 is adapted to slide upon the support 34 and the construction to accomplish this is shown more particularly in Fig. 11. The board 60 is provided with two engaging members 70, secured to the back of the board by two separating members 71. The engaging members 70 are mounted so as to overlie the extensions 38 on support 34. The board is placed upon the support 34 by sliding it into position with the extensions 38 sliding in the space provided by the overlapping members 70. In this way the board 60 can be slid up and down the support 34 at any position. The members 70 and 71 extend the full length of the board and coact with the extensions 38 which extend the full length of the support 34 to provide support throughout the length of the board, preventing sidewise motion of the board at any position of the board.

Across the bottom of the drawing board are ledges 61 on which a drawing can be rested. These are preferably formed with an inclined surface 61a (Fig. 6) so that the drawing will be held firmly against the board 60 by falling to the bottom of the incline. Located between the ledges 61 is a large thumb screw 62 which is used for fastening the easel or board 60 in firm engagement with the support 34. The details of this fastening means are shown more particularly in Figs. 12 and 13. A rectangular hole 63 is cut into the bottom of the board, between the ledges 61. Into the hole is fitted a rectangular block 64 of about the same size. Mounted across the hole and secured to the board is an overlying piece 65. A threaded bolt 66 extends through the cross piece 65 into the block 64. On the end of this bolt is mounted the thumb screw 62. When the screw 62 is turned, the block 64 is pressed into firm engagement with the support 34, thereby forcing the block 64 against the support 34 and securing the board 60 at any position up or down the length of the support 34. The engaging face 64 of the block may be roughened or may be covered with sandpaper or an adhesive so as to facilitate holding the board firmly in position. This construction is important since the large area provided by the block 64 against the support 34 is sufficient to hold the weight of the board 60 firmly in position.

When the thumb screw 62 is turned so as to press the block 64 against the surface 34, the extensions 70 on the board 60 will be brought into firm engagement with the extensions 38 on the support 34 and the board 60 will be held in rigid fixed position relative to the support 34. The support in turn is held firmly by the triangular plate 33 and the piano hinge 30.

In the construction shown in Figs. 1 and 6 the surface 60 is used in the manner of an easel, i. e., positioned above the surface of the lid 12. The easel may be raised or lowered by means of the thumb screw 62, and by means of the screws 51 and 52 it may be placed in a vertical position, as shown in Fig. 6, or it may be inclined to any angular position, as shown in Fig. 1.

When the canvas is too large, the support 60 can be extended, as shown more particularly in Fig. 6. In this modification the upper end of the board 60 is formed separately as shown at 80 and has mounted therein two rods 81 which extend through openings 82 and are held in position in the extensions 83 and 84 by means of

thumb screws 85 and 86. These extension rods may be fastened in position and the extension piece 80 extended to any desired distance. The upper end of the extension contains a ledge 87 which corresponds to the lower ledge 61 in the bottom and has an inclined surface 88 at the top similar to the inclined surface 61a at the bottom. When the canvas or other material on which the painting is to be done is large, it can be placed on the board 60 with the lower edge resting against the inclined surface 61a and the edge 88 brought into firm engagement with the upper end of the canvas. When the ledges 61a and 88 are clamped in position by screws 84 and 85 the canvas will be held firmly on the easel.

In the above description, the support 60 is illustrated as an easel, as shown in Fig. 1. However, it may be used as a drawing board by reversing its position 180° and sliding the surface 60 upon the support 34 so that the holding screw 62 is at the top of the board instead of the bottom, as shown in Fig. 4. In this way the supporting surface 60 may be dropped down in front of the compartment 19, since the supporting block 64 at the top of the drawing board may be brought into supporting engagement near the bottom of the support 34. In this way the drawing board can be dropped down so as to be between the knees or in the lap of the artist sitting in front of it, a position often found convenient.

The pallet mounting construction is described as follows: On the left and front corner of the upper inside surface of the lid 12 is an angular metal piece 90 which is fastened on the surface 35 of the lid 12. The hinges 15 raise the lid 12 from the surface 16 sufficiently to permit a U-shaped member 91 to be inserted over the lid and fastened in position by means of a thumb screw 92. Attached to this U-shaped member is an additional support 93 to receive a tubular member 94 which can be held in fixed position by means of a thumb screw 95. The tubular member 94 is a part of an angular piece having two arms 96 and 97, the latter being vertically positioned to engage a socket 98 mounted on the bottom of each of the pallets 26. The socket in the bottom of the pallet is spaced off-center and by rotating the pallet around the supporting vertical member 97 and by positioning the supporting arm 96 at various positions upon loosening the thumb screw 95, it is possible to adjust the pallet to any desired position. The rims on the pallet 26a are such that paint can be left upon the pallets when they are placed upon the paint boxes 24 and 25 and will thus protect the paint when the drawing board is lowered to hold the pallets in position on top of the paint boxes.

Another feature of the invention is the provision of an artist's maul which extends between the two ledges 61 and 87. The maul is formed with two telescopic members, the outer being a tubular member 100 and the inner a tubular member 101 sliding within the outer member. Extending throughout the length of the two members is a spring fastened at each end which normally tends to hold the member 101 telescoped inside the member 100. The inner member 101 may be pulled out of the outer member 100 against the tension of the spring. On the end of the outer member 100 is a right angular engaging member 102 with a point which engages the surface of the ledge 61 and on the end of member 101 is an engaging member with a point 103 which engages the upper surface of the ledge 87. The maul 70 can be placed in position by pulling the mem-

ber 101 out from the outer member 100 and permitting the spring to pull the points 102 and 103 against the ledges 61 and 81, holding the maul in position. The ledges 61 and 81 hold the maul away from the drawing located flat against the surface 60 and in this way a rest is provided for the artist's hand.

It is not essential that all of the features be included in the embodiment of my invention. For example, the maul may be omitted if desired, as well as the pallet support. These members are normally carried within the space in the trunk and may be optional equipment.

It will be obvious that there may be many variations and modifications of the precise construction shown without departing from the inventive concept disclosed and all such as are within my claims are intended to be included.

I claim:

1. A container adapted to comprise all of the equipment and supplies ordinarily required by an artist, including a hinge closure for said container normally occupying a vertical side position when closed and openable to a horizontal plane resting upon the upper top surface of the container, a supporting member mounted upon said closure, means for adjusting said supporting member to vertical and different angular positions, a painting and drawing surface mounted for engagement with said supporting member at any of different positions along the same, and means mounted near one end of said surface for clamping said surface to said supporting member, said means comprising a movable block located within the area of said surface and a screw-operated member for urging said block against said supporting member.

2. A container adapted to comprise all of the equipment and supplies ordinarily required by an artist, including a hinge closure for said container normally occupying a vertical side position when closed and openable to a horizontal plane resting upon the upper top surface of the container, a supporting member mounted upon said closure, means to fasten said supporting member to said closure comprising a triangularly shaped piece and a piano-type hinge extending continuously along the bottom of said triangularly shaped piece and into engagement with said closure, means for adjusting said supporting member to vertical and different angular positions, and a painting and drawing surface mounted for engagement with said supporting member at any of different positions along the same.

3. A container adapted to comprise all of the equipment and supplies ordinarily required by an artist, including a hinge closure for said container normally occupying a vertical side position when closed and openable to a horizontal plane resting upon the upper top surface of the container, a supporting member mounted upon said closure, means to fasten said supporting member to said closure comprising a trian-

gularly shaped piece secured to said supporting member, a rectangular piece secured to said closure, a piano hinge extending continuously along the said triangularly shaped and rectangular pieces, means for adjusting said supporting member to vertical and different angular positions, a painting and drawing surface mounted for engagement with said supporting member at any of different positions along the same, and means mounted near one end of said surface for clamping said surface to said supporting member.

4. A container adapted to comprise all of the equipment and supplies ordinarily required by an artist, including a hinge closure for said container normally occupying a vertical side position when closed and openable to a horizontal plane resting upon the upper top surface of the container, a supporting member mounted upon said closure, means to fasten said supporting member to said closure comprising a triangularly shaped piece and a piano-type hinge extending continuously along the bottom of said triangularly shaped piece and into engagement with said closure, means for adjusting said supporting member to vertical and different angular positions, a painting and drawing surface mounted for engagement with said supporting member at any of different positions along the same, and means mounted near one end of said surface for clamping said surface to said supporting member, said means comprising a movable block located within the area of said surface and a screw-operated member for urging said block against said supporting member.

5. In a device of the type described, an elongated supporting member, means for adjusting said supporting member to vertical and different angular positions and for fixing it in any of said positions, a painting and drawing surface mounted for engagement with said supporting member at different positions along the same, and means mounted near one end of said surface for fastening said surface to the supporting member, whereby said surface may be mounted on said supporting member to extend beyond either end of said elongated supporting member.

MICHAEL DOLAS.
